DEVICE FOR HYPODERMIC INJECTIONS

Paul Kollman, New York, N. Y.

Application December 20, 1947, Serial No. 792,994

3 Claims. (Cl. 128—220)

1

This invention relates to improvements in devices for hypodermic or intra-muscular injection of medicinal compositions.

Among other features and improvements, this invention provides a novel and improved device which combines the functions of an ampule for storing a predetermined volume of a medicinal composition with the functions of an injection syringe so that the volume of medicinal fluid contained in the device may be directly injected into live tissue without previous transfer to a separate syringe.

The improved device is hereinafter sometimes referred to as an "injector ampule" and offers a great many advantages over conventional ampules and separate injection syringes, in that the device is always ready for immediate use, that the volume of fluid contained therein is of a pre-determined and accurate magnitude, and in that all its vital portions, for example its needle and its front end are maintained sterile up to the time of removal of factory applied seals; that is, up to the time of injection.

The novel injection syringe does away with the necessity of preparing, sterilizing and filling hypodermic syringes, an operation usually calling for considerable mechanical skill. It is so constructed as to insure sterility and freedom of the enclosed volume of fluid from gas or air bubbles. A sharp new needle point is available for each injection, thus doing away with difficulties arising from worn or not well cared for injection syringes and their attachable needles.

The invention provides many other advantages which will become apparent from a consideration of its structure and operation hereinafter described in greater detail.

Injector ampules are primarily designed for one-time use and are intended to be discarded after discharge of their contents.

Since storage of a predetermined volume of a medicinal composition is a portion of the function of the injector ampule, it is, of course, necessary that the device be conveniently fillable by the manufacturer, that it be tightly sealable and that it be able to withstand a considerable amount of careless handling and abuse without impairment of its important functions and characteristics. Consisting of telescoping or collapsible parts and generally made of a non-shatterable plastic composition, it is constructed to withstand dropping without loss of sterility of its important parts.

If a filled injection syringe or an injector ampule is dropped, extremely high pressures are

2

temporarily set up within its fluid chamber. Tests conducted with ordinary injection syringes show that the pressures thus created are sufficient to blow off sealing plugs at the end of the 5 needle and blow off or loosen needles frictionally attached to the syringe barrel by means of fittings or so-called adapters. As a result, not only fluid is lost, but the device is rendered non-sterile and its further use is objectionable. However, 10 experience has shown that proper precautions are frequently disregarded by laymen or irresponsible personnel and that instead of discarding the device after dropping, loose parts are frequently reattached in spite of the fact that the device is 15 no longer safe for use.

The present invention provides a device which for all practical purposes eliminates the aforementioned dangers. It is so constructed that the injection needle can not be blown off or be lost 20 or be removed and reattached, and it is so constructed that it is capable of withstanding high pressures if accidentally dropped or otherwise carelessly handled.

These and various other features, advantages 25 and objects of the invention will appear more fully from the detailed description which follows accompanied by drawings showing, for the purpose of illustration, preferred embodiments of the invention. The invention also consists in certain 30 new and original features of construction and combination of elements hereinafter set forth and claimed.

Although the features characteristic of this 35 invention which are believed to be novel will be particularly pointed out in the claims appended hereto, the invention itself, its objects and advantages and the manner in which it may be carried out may be better understood by referring to the following description taken in connection 40 with the accompanying drawings forming a part of this application in which:

Figure 1 is a cross-sectional side view of an injector ampule embodying the invention;

Figure 2 is a cross-sectional side view of a modified form of injector ampule;

Figure 3 is a fractional cross-sectional side view of the needle and front end of a modified form of injector ampule similar to the form shown in Figure 2; and

Figure 4 is a cross-sectional side view of a further modified form of injector ampule of a construction similar to that shown in Figure 2.

In the following description and in the claims, various details will be identified by specific 55 names for convenience. The names, however,

are intended to be generic in their application. Corresponding reference characters refer to corresponding parts in the several figures of the drawings.

In the drawings accompanying and forming part of this specification, certain specific disclosure of the invention is made for the purpose of explanation of broader aspects of the invention, but it is understood that the details may be modified in various respects without departure from the principles of the invention and that the invention may be applied to other structures than the ones shown.

The subject matter of this application is related to the subject matter of co-pending applications directed to devices of the general type disclosed herein.

Application Serial No. 792,991, filed December 20, 1947, discloses and claims a syringe in which the depth of insertion is automatically controlled and limited, and in which stop means are provided permitting measured partial discharge.

Application Serial No. 792,992, filed December 20, 1947, discloses and claims a syringe designed for one-time use and so arranged that it cannot be reused.

Application Serial No. 792,993, filed December 20, 1947, discloses and claims a tubular needle seal for a syringe which prevents contamination of the needle and is blow-off proof in that it will not blow off if the syringe fluid is subjected to a sudden rise in pressure, for example by dropping the syringe.

Application Serial No. 792,995, filed December 20, 1947, discloses and claims an improved form of non-creeping plunger seal.

The injector ampule shown in Figure 1 comprises a barrel 11 within which a plunger 12 is telescopically movable. The plunger 12 is tightly sealed with respect to the interior surface 13 of the barrel by a gasket 14 which rests in a groove 15 of the plunger and frictionally engages the interior surface 13 of the barrel.

The rear surface 16 of the plunger forms a movable wall of the chamber 17 adapted to contain and store a charge of medicinal fluid confined between the barrel 11 and the plunger 12.

A hollow injection needle 18, preferably of substantially uniform outer diameter, is mounted in the front end 19 of the plunger 12 and communicates with the chamber 17 through a hollow passage 20 extending through the plunger.

The barrel 11 and the plunger 12 are preferably made from a synthetic moldable plastic of a type that will retain its shape within the range of temperatures in which the device is used and stored, but which will become deformed if subjected to sterilizing temperatures of the order of the temperature of boiling water. Such construction discourages sterilizing of the syringe by the user for the purpose of using it the second time, but does not prevent original sterilizing by the manufacturer which is preferably accomplished by exposing the device to a stream of sterilizing gas of a temperature sufficiently low as not to cause changes in the dimension of the parts.

The use of a moldable plastic makes it possible to imbed the needle 18 in the front end 19 of the plunger 12 by molding the plastic material around the needle so that the needle is firmly, by pressure, tightly and non-removably held within the plunger.

The rear surface 16 of the plunger is prefer-

ably tapered to facilitate the expulsion of air or gas bubbles which collect at the entrance of the passage 20 if the device is held in a vertical position. Slight telescoping movement is then sufficient to expel the bubble from the syringe. This is greatly facilitated by making the plunger 12 of a transparent clear plastic so that the passage of gas bubbles through the plunger can be observed. The passage 20 is preferably clear and transparent up to the end 21 of the needle so that gas bubbles can be observed to enter and pass through the needle 18. In this manner absolute freedom from air and gas bubbles is positively insured.

The cylindrical body of the plunger, by reason of its transparency, acts as a cylindrical magnifying lens for the transparent passage portion 20 and makes the contents of that passage easily observable. This is a valuable feature of the illustrated construction making the device particularly suited for use under conditions where aspiration is desired as a pre-injection test to determine whether a blood vessel was punctured by insertion of the needle. Slight withdrawal of the barrel 11 relatively to the plunger 12 causes a minute quantity of body fluids to be drawn into the passage 20. The magnifying property of the plunger makes it particularly easy to determine whether blood is contained in the body fluid.

The needle 18 is preferably made of substantially uniform outside diameter to permit insertion of its entire exposed length 1 into the tissue of the patient. The depth of insertion is thus positively limited by the front surface 22 of the plunger which rests against the skin of the patient and acts as a stop.

In order to maintain the housing of the injector syringe out of contact with the skin of the patient immediately adjacent the shaft of the needle 18, a cavity 23 is preferably formed in the front end of the syringe housing. The cavity 23 preferably has tapered side walls 24 enabling pressure-tight insertion of a sealing cap 25 of suitable construction and also permitting pressure tight application of a spout or nozzle 26 at the end of a filling duct 27, as indicated in Figure 2.

Figure 2 illustrates a modified form of injector syringe comprising a barrel 30 within which a plunger 31 is telescopically movable. The plunger has an enlarged finger operable grip portion 32 for convenient handling. A suitably constructed movable seal or membrane 33 which may be separate from the plunger 31, is telescopically movable in the barrel 30 and forms a seal for the fluid chamber 34 with respect to the plunger 31.

An injection needle 35 is permanently mounted in the front end 36 of the barrel 30, preferably by molding the injection needle into the plastic material of the barrel during its manufacture.

The bore of the needle 35 communicates with the chamber 34 through a passage 37 which is preferably visible from the outside by making the barrel 30 of a clear transparent material.

The front end surface 38' of the chamber 34 is preferably tapered to cause bubbles to collect at the entrance of the passage 36 for easy removal.

A cavity 39 preferably having tapered side walls 40 is formed in the front end 36 of the barrel. This cavity serves the multiple purpose of maintaining the body of the injector syringe out of contact with the skin of the patient im-

mediately adjacent the needle 35, the further purpose of receiving a sealing cap of suitable construction as indicated at 25 in Figure 1 and serves further the purpose of receiving a spout or nozzle 26 of a duct 27 through which the injector syringe may be filled. The duct 27 leads to a source of fluid under pressure (not shown).

The injector syringe shown in Figures 1 and 2 is supplied by the manufacturer filled with a predetermined volume of fluid. The syringe is sealed by affixing a sealing cap 25 which preferably forms a double seal. It seals the end of the needle 18 or 35, respectively against discharge of liquid or fluid, the seal being sufficient to withstand great pressure by reason of its acting on a surface of extremely small area, that is, the end of the needle. In addition, a second seal is formed between the cap 26 and the front end of the housing. This seal is not only a pressure-tight seal, but also one which maintains the base of the needle sterile and protects the needle against contamination when the cap is being removed, it being apparent that only the protected sterile end portion of the cap slides along the shaft of the needle.

After removal of the sealing cap 25, the device is ready for use. It is preferably applied to the body of the patient by grasping it at the barrel 11 providing a finger grip portion 28 or by grasping it at the finger grip surface 32 in the syringe illustrated in Figure 2. The needle 18 or 35, respectively, is placed on the patient's skin and pressure is then exerted in the direction of the needle to force it into the body tissue.

In order to compel insertion of the needle at right angles to the skin of the patient, the length l of the needle is preferably made less than the outside diameter of the housing member in which it is mounted.

Application and insertion of the needle does not cause any liquid to be discharged from the syringe because of initial friction of considerable magnitude between the wall of the chamber 17 or 34, with a seal 14 and 33, respectively. This friction is high while the plunger is at rest and by appropriate selection of the dimension of the seal with respect to the dimensions of the barrel is made to amount to a multiple of the force required for inserting the needle into body tissue to its full length.

As the front surface 22 or 38', respectively, of the syringe housing comes to rest on the patient's skin, the pressure exerted at the syringe is opposed by an equal pressure of the skin against the syringe with the result that the friction of the gasket is overcome and the liquid is expelled from the chamber 17 or 34, respectively, into the patient's body tissue.

Figure 3 illustrates a modification of the front end formation of a barrel 30' in which a male sealing surface 41 is formed on a plug or base 42 inserted with a press fit into the front end 36' of the barrel 30'. In this form of device, the needle 35' is molded into the base or plug 42 and the base or plug 42 is inserted under great pressure into an appropriate cavity 43 of the barrel 30' so as to become virtually a part of it and to be non-removable therefrom.

The plug or base 42 is adapted to receive a female sealing portion of an appropriately shaped sealing plug or filling nozzle. In the form of injector syringe shown in Figure 3, the size of the plug or base 42 with respect to the front end surface 38' is so selected that the front

end surface acts as a stop limiting the depth to which the needle 35' may be inserted into body tissue.

The form of injector ampule shown in Figure 5 is similar in all respects to the construction shown in Figure 2, except for the detailed construction of the plunger 31' whose seal 14' rests in a groove 15' so that the plunger 31' may be slightly withdrawn in order to draw a small quantity of body fluids into the transparent passage 37 for the purpose of testing whether insertion of the needle 35 caused injury to a blood vessel. The cylindrical front portion 31'' acts as a magnifying lens for the passage 37 so that its contents can be conveniently observed.

The invention thus provides a simple and highly useful device for the storage and injection of predetermined volumes of medicinal composition. It is inexpensive to manufacture by modern mass production methods, is simple to fill and convenient to operate. It eliminates many of the prevailing disadvantages inherent in the practice of sterilizing and filling conventional injection syringes from ampules. Devices embodying the present invention are particularly suited for application by the patient himself. If used on a professional scale by doctors and nurses, a considerable saving in time is experienced.

Obviously, the present invention is not restricted to the particular embodiments herein disclosed. Numerous modifications, additions, omissions, substitutions and various other changes may be made without departure from the spirit and the essence of the invention as set forth in the appended claims. Such changes will suggest themselves to persons familiar with the disclosure of this invention and do not involve a departure from the spirit and the teachings of the invention.

What is claimed is:

1. A combination ampule and injection syringe for storing and injecting a predetermined volume of medicinal fluid, comprising, a barrel member; a plunger member telescopically movable in said barrel member and forming a variable volume chamber therewith adapted to contain a charge of medicinal fluid at least one of said members being of cylindrical shape and made of a clear transparent plastic; and an injection needle of substantially uniform outer diameter irreplaceably imbedded in the front of said one member, said one member having a cylindrical passage into which said needle extends, the length of the needle portion imbedded in said one member being less than the length of said passage, said passage appearing optically magnified through the body of said one member, said one member further having a funnel-shaped mouth portion at the end of said passage towards said chamber for guiding bubbles in the chamber into said passage when the syringe is held in a substantially vertical position.

2. A combination ampule and injection syringe for storing and injecting a predetermined volume of medicinal fluid, comprising, a barrel member; a plunger member telescopically movable in said barrel member and forming a variable volume chamber therewith adapted to contain a charge of medicinal fluid; an injection needle of substantially uniform outer diameter irreplaceably imbedded in the front end of one of said members, said last named member having a substantially flat front surface and a cavity

in said front surface surrounding the base of the needle, said cavity preventing contact of said one member with the skin of the patient immediately adjacent the needle.

3. A combination ampule and injection syringe for storing and injecting a predetermined volume of medicinal fluid, comprising, a barrel member; a plunger member telescopically movable in said barrel member and forming a variable volume chamber therewith adapted to contain a charge of medicinal fluid; an injection needle of substantially uniform outer diameter irreversibly imbedded in the front end of one of said members, the free length of the needle protruding therefrom being less than the outside diameter of said one member, said last-named member having a flat front surface and a cavity in said front surface surrounding the base of the needle, said cavity preventing contact of said one member with the skin of the patient immediately adjacent the needle.
